GARBAGE CAN STAND

Gustavo M. Figueroa, 832 E. Lester St., Tucson, Ariz., assignor of fifty percent to R. M. Figueroa, Yuma, Ariz.

Filed July 24, 1961, Ser. No. 126,135

8 Claims. (Cl. 248—149)

This invention relates to a novel and useful garbage can stand which is specifically adapted to support a garbage can in an elevated position above ground level. The garbage can stand of the instant invention is adapted to be semi-permanently secured to the ground from which it is supported and includes means for supporting a garbage can in an elevated position above ground level, embracing a portion of the garbage can disposed above the bottom thereof. In this manner, the garbage can will be supported in a manner which will resist lateral forces such as wind and nudging by animals which might normally upset the garbage can.

The garbage can stand is constructed of durable metallic materials and the portions thereof which are adapted to come in contact with the garbage can being supported are covered or cushioned by resilient and soundproofing materials such as rubber.

The main object of this invention is to provide a garbage can stand for supporting a garbage can in a slightly elevated position above ground level.

Another object of this invention is to provide a garbage can stand which will not only provide a support for the bottom of the garbage can but also provide a means for loosely embracing an upper portion of the garbage can thereby preventing the garbage can from being accidentally tipped over by wind or by animals such as dogs.

Still another object of this invention is to provide a stand constructed of durable metallic materials but with the portions of the stand adapted for engagement with a garbage can covered with suitable sound-deadening resilient materials such as rubber.

Another object of this invention is to provide a garbage can stand provided with means for forming an open top enclosure immediately beneath the garbage can supported by the stand and having a plan area larger than the plan area of the garbage can which is being supported whereby pieces of trash and the like which often accidentally fall out of a can will be enclosed and thus not present an eyesore.

A final object to be specifically enumerated herein is to provide a garbage can stand which will conform to conventional forms of manufacture, be of simple construction and easy to use so as to provide a device that will be economically feasible, long lasting and relatively trouble free in operation.

These together with other objects and advantages which will become subsequently apparent reside in the details of construction and operation as more fully hereinafter described and claimed, reference being had to the accompanying drawings forming a part hereof, wherein like numerals refer to like parts throughout, and in which:

FIGURE 1 is a top plan view of the garbage can stand of the instant invention;

FIGURE 2 is a side elevational view of the stand shown supporting a garbage can;

FIGURE 3 is an enlarged fragmentary vertical sectional view taken substantially upon a plane indicated by the section line 3—3 of FIGURE 2;

FIGURE 4 is an enlarged fragmentary horizontal sectional view taken substantially upon the plane indicated by the section line 4—4 of FIGURE 3;

FIGURE 5 is an enlarged fragmentary vertical sectional view taken substantially upon the plane indicated by the section line 5—5 of FIGURE 1;

2

FIGURE 6 is a fragmentary exploded perspective view of a portion of the stand;

FIGURE 7 is a fragmentary enlarged vertical sectional view taken substantially upon a plane indicated by the section line 7—7 of FIGURE 5; and

FIGURE 8 is a fragmentary enlarged side elevational view of a portion of one of the diagonal braces of the stand with parts broken away and shown in section.

Referring now more specifically to the drawings and to FIGURES 1, 3 and 6 in particular, the numeral 10 generally designates the garbage can stand of the instant invention. It will be noted that the stand 10 is adapted to be supported by the ground 12 and that in order to provide a semi-permanent installation a hole 14 has been formed in the ground 12 and filled with concrete or similar material 16 having a rod 18 embedded therein.

The garbage can stand includes upper and lower generally cylindrical rings 20 and 22 which are interconnected by means of four upstanding and circumferentially disposed uprights 24. The uprights 24 may be secured to the upper and lower rings 20 and 22 in any convenient manner such as by fasteners 26 and 28 respectively.

An embracing ring generally referred to by the reference numeral 30 is supported concentrically within the upper ring 20 by means of a plurality of expansion springs 32 secured between the larger ring 20 and the smaller inner embracing ring 30. The embracing ring 30 may either be constructed of a metallic material and covered by a resilient covering such as rubber, or the ring 20 may be entirely constructed of a resilient semi-rigid material such as rubber. The opposite ends of the expansion springs 32 are secured to the rings 20 and 30 by means of J-shaped fasteners 34.

The upper end of the ring 20 is provided with a radially extending flange 36 and the lower end of the ring 22 is provided with a radially extending and outwardly projecting flange 38. The lower ends of the uprights 24 include inwardly directed terminal end portions 40 which are adapted to engage the upper surface of the ground 12 and prevent the stand 10 from sinking relative to the ground 12.

A pair of generally inverted U-shaped braces referred to in general by the reference numeral 42 are secured between the opposite uprights 24 in any convenient manner such as by fasteners 44 secured through the aligned bores 46, 48 and 50 formed in the lower ring 22, the corresponding uprights 24 and the downturned end portions 52 of the inverted U-shaped braces 42 respectively.

It will be noted that the lower ring 22 and the uprights 24 each include a third pair of aligned bores 48 and 50 whose purpose is to be hereinafter more fully set forth.

Two pair of diagonal brace members 54 having angulated end portions 56 and 58 are secured between each pair of opposite uprights 24 and the corresponding inverted U-shaped brace 42. It will be noted that the mid portion of each brace 42 is provided with a pair of apertures 60 and 62 and that the lower angulated end portion 58 of each diagonal brace 54 is provided with an aperture 64. The fasteners 26 utilized to secure the upper ends 60 of the uprights 24 to the upper ring 20 are also secured through the angulated end portions 56 of the diagonal braces 54 and it will be noted that an abutment member generally referred to by the reference numeral 66 is secured to each of the diagonal braces 54 by means of a pair of fasteners 68 and 70. The abutments 66 may each be constructed of resilient material and it will be noted that the diagonal braces 54 may either be constructed of a resilient material such as rubber or a metallic substance and then covered with a covering of resilient material such as rubber.

The inverted U-shaped braces 42 are each provided with a central bore 72 and the upper end of the rod 18

is threaded as at 74 and is passed through the registered bores 72. A suitable fastener such as nut 76 may be secured to the upper end portion of the rod 18 which projects through the inverted U-shaped braces 42.

In operation, the bottom of the garbage can 80 is inserted downwardly through the embracing ring 30 and is engaged with the upper surfaces of the abutment 66. It will be noted that the diagonal brace members 54 immediately adjacent the upper surface of the abutment 66 coact with each other to embrace and properly center the lower end of the can 80 in the stand 10. The resiliently mounted embracing ring 30 will of course prevent the upper end of the can 80 from being tilted and thus maintain the can upright.

If it is desired to alter the stand 10 to accommodate a larger garbage can, the fasteners 82 secured through the registered bores or apertures 62 and 64 may be removed and the fastener 82 may be secured through the bores 60 and 64. In this manner, the lower ends of the diagonal braces 54 will be moved apart in order to accommodate a can of greater diameter than the can 80. However, when moving the lower ends of the diagonal braces 54 apart, the inverted U-shaped braces 42 must be lowered. Accordingly, the fasteners 44 are removed and the fasteners 44 may be secured through the lower pair of bores or apertures 46 and 48 and the bores 50 formed through the downturned end portions 52.

It is to be noted that when the can 80 is positioned within the stand 10, the handles of the can 80 will be disposed a spaced distance above the bracing ring 30. Additionally, if it is desired not to semi-permanently secure the stand 10 to the ground 12, the rod 18 can be omitted and a fastener substituted therefor secured through the registered bores or apertures 72.

The foregoing is considered as illustrative only of the principles of the invention. Further, since numerous modifications and changes will readily occur to those skilled in the art, it is not desired to limit the invention to the exact construction and operation shown and described, and accordingly all suitable modifications and equivalents may be resorted to, falling within the scope of the invention as claimed.

What is claimed as new is as follows:

1. A garbage can stand comprising an upright support frame adapted to be supported from a generally horizontally disposed supporting surface and including support means adapted to support a garbage can from the bottom and in an elevated position above said supporting surface, said frame including means adapted to embrace a portion of said can above the bottom thereof, said embracing means including an annulus resiliently suspended from an upper portion of said support frame, said support frame including means for vertically adjusting said support means, said support means also including means adapted to snugly embracingly engage the lower portion of said can adjacent the bottom thereof, said last-mentioned embracing means including adjustable means for snugly embracing cans of various diameters and also means for adjusting the vertical height of said support means upon adjustment of said last-mentioned embracing means.

2. A garbage can stand comprising a support frame adapted to be supported from a generally horizontally disposed supporting surface and including means adapted to support a garbage can from the bottom and in an elevated position above said supporting surface, said frame including means adapted to embrace a portion of said can above the bottom thereof and means forming an open

topped enclosure about the lower portion of said frame below said supporting means larger in plan area than the plan area defined by said embracing means, said embracing means including means resiliently supported from said support frame, and said support frame including means for vertically adjusting said support means, said support means also including means adapted to snugly embracingly engage the lower portion of said can adjacent the bottom thereof, said last-mentioned embracing means includes adjustable means for snugly embracing cans of various diameters and also means for adjusting the vertical height of said support means upon adjustment of said last-mentioned embracing means.

3. A garbage can stand comprising an upright support frame adapted to be supported from a generally horizontally disposed supporting surface and including support means adapted to support a garbage can from the bottom and in an elevated position above said supporting surface, said frame including means adapted to embrace a portion of said can above the bottom thereof, said embracing means including means resiliently supported from said support frame, said support means including at least two pairs of inclined downwardly convergent brace members disposed circumferentially about the center or vertical axis of said support frame, each of said brace members including an abutment projecting laterally therefrom toward said vertical axis and adapted to support the lower surfaces of said can.

4. The combination of claim 3 including generally horizontally disposed brace members interconnecting the lower ends of said inclined brace members.

5. A garbage can stand comprising an upright support frame adapted to be supported from a generally horizontally disposed supporting surface and including support means adjacent its lower end adapted to support a garbage can from the bottom and in an elevated position above said supporting surface, said frame also including a horizontally disposed open frame-like brace member adjacent its upper end disposed above and in general vertical alignment with said support means, a horizontally disposed open frame-like ring disposed generally concentrically within said brace member, and a plurality of elongated resilient members secured between said brace member and said ring and spaced circumferentially about said brace member and ring resiliently suspending said ring from said frame-like brace member.

6. The combination of claim 5 including means carried by the lower portion of said support frame defining an open top enclosure about the lower portion of said frame below said supporting means, said enclosure being larger in plan area than the area defined by said frame-like ring.

7. The combination of claim 5 wherein said open frame-like ring is constructed of resilient material having sound deadening properties.

8. The combination of claim 5 wherein said support frame includes means for vertically adjusting said support means.
